A. MILLER

VENTILATOR

Filed April 18, 1925

Fig. 1.

Patented Aug. 9, 1927.

1,638,698

UNITED STATES PATENT OFFICE.

ARTHUR MILLER, OF ASTORIA, NEW YORK.

VENTILATOR.

Application filed April 18, 1925. Serial No. 24,129.

This invention relates to an improvement in ventilators and has for its object to provide a ventilator for exhaust pipes for foul air, smokestacks, or the like, which structure is so arranged that currents of air blowing from any direction will be prevented from passing down the main pipe, but will be directed upwardly and downwardly by vertically disposed channels which are blanketed at their ends from the cross or horizontal currents of air by annular bands. By directing the air in columns and in substantially vertical paths adjacent the outlet of the main pipe, a vacuum or suction will be created in and around the outlet of the pipe and thereby effectively exhaust the foul air or gases in the pipe or stack.

Another object is to provide a ventilator which is simple, durable, efficient and economical to manufacture.

Another object is to provide certain improvements in the form, construction and arrangement of the parts whereby the above named and other objects may be effectively attained.

A practical embodiment of my invention is represented in the accompanying drawing, in which

Fig. 1 represents an elevation partly in section of my improved ventilator attached to a portion of a pipe or smoke-stack.

Fig. 2 represents a plan view, partly in section, of the same.

Fig. 3 represents a detail vertical section taken in the plane of the line III—III of Fig. 2, looking in the direction of the arrows, and

Fig. 4 represents a detail vertical section of a modified form of cap.

The exhaust pipe or smoke-stack is denoted by 1 and my improved ventilator is secured thereto by means of brackets, in the present instance, four are shown, each of which brackets is provided with a vertical portion 2 and an inwardly curved portion 3, the inner end of which is bent laterally to form a foot 4 which is secured to the pipe 1 by a bolt 5 and nut 6 or other suitable means.

The outer element of the ventilator has the general formation of two frustums of cones united at their bases, the walls of which are curved inwardly from the bases and toward a vertical direction. The upper member or frustum 7 is provided with an inwardly and upwardly curved wall 8 having radially disposed partitions 9 forming

ing a series of tapered channels 10. An annular band 11 is secured to the upper end of the partitions 9, the association of which forms a series of tubular passages 12.

The lower member or frustum 13 is provided with an inwardly and downwardly curved wall 14 having radially disposed partitions 15 forming a series of tapered channels 16 which terminate in a series of tubular passages 17 constructed by locating and securing an annular band 18 to the lower end of the partitions 15. The bands 11 and 18 are shaped to conform to the curvature of the outer edges of the partitions 9 and 15. The member 13 together with its band 18 is held in position on the vertical portion 2 of the brackets by notching the vertical portion 2 and bending outwardly the portion 19 which receives and supports the member and its band.

To secure the upper member 7 and band 11 in position on the brackets, I cut a notch in the vertical portion 2 and bend the free portion 20 outwardly so as to extend over 80 the member and band.

A cap 21 is inserted within the ventilator, the vertical wall 22 of which is spaced from the member 7 and its curvature is substantially parallel to the wall 8 of the member. 85 The lower edge of the wall 22 is arranged to rest upon a notch 23 on the inner edge of the vertical portion 2 of each of the brackets and extends over the pipe 1 to prevent rain and other foreign matter from entering the 90 pipe.

In the form shown in Figs. 1 to 3 inclusive the cap 21 is spaced from the wall 8 of the member 7 to form a substantially vertical passage 24 for the exit of the air 95 or gases from the pipe. To deflect the upward movement of the gases from the passage 24, I extend the cap above the member 7 and band 11 and flare it outwardly as shown at 25.

A similar passage 26 is also formed between the pipe and the wall 14 of the member 13 to exhaust the air or gases therebetween.

In Fig. 4 I have shown a cap 27 formed of glass or other transparent material so that light may be admitted therethrough. This cap is supported on lugs 28 extending inwardly from the vertical portion 29 of the brackets, which brackets are constructed and arranged similar to the brackets shown in Figs. 1 to 3 inclusive.

From the foregoing, it will be seen that as the air currents strike the members 7 and 13 they will be deflected upwardly and downwardly through the tapered channels 10 and 16 into the tubular passages 12 and 17, thereby creating a vacuum or suction adjacent the passages 24 and 26, which suction will draw the impure or warm air and gases from the pipe into the center of the members 7 and 13, thence outwardly through the passages 24 and 26.

From the foregoing description it will be seen that a very simple and durable ventilator has been produced, which will effectively cause a continuous suction adjacent the upper end of the pipe for exhausting foul air, smoke or gases therefrom and which can be manufactured at an exceedingly low cost.

It is obvious that various changes may be resorted to in the form, construction and arrangement of the several parts without departing from the spirit and scope of my invention; and hence, I do not intend to be limited to the details herein shown and described except as they may be included in the claims.

What I claim is:—

1. A ventilator comprising a pipe, an element disposed above and laterally from said pipe, said element having a series of curved tapered channels disposed longitudinally on its exterior for deflecting the air currents in substantially vertical paths, and a cap provided with a depending wall within the element and spaced therefrom for protecting the pipe and providing an outlet therebetween.

2. A ventilator including, a pipe, an element disposed above and laterally from said pipe, said element comprising a curved cylindrical body portion having a plurality of vertically and radially disposed ribs developed from said body portion and arranged to form a series of longitudinally curved tapered channels on its exterior for deflecting air currents in substantially vertical paths, and a cap provided with a depending wall within the element and spaced therefrom for protecting the pipe and providing an outlet therebetween.

3. A ventilator comprising a pipe, an element disposed above and laterally from said pipe, said element having a series of oppositely curved tapered channels disposed longitudinally on its exterior for deflecting the

air currents in substantially vertical paths, and a cap provided with a depending wall within the element and spaced therefrom for protecting the pipe and providing an outlet therebetween.

4. A ventilator comprising a pipe, an element disposed above and laterally from said pipe, said element having channels on its exterior, tubular passages coacting with said channels for deflecting the air currents in substantially vertical paths, and a cap within the element and spaced therefrom for protecting the pipe and providing an outlet therebetween.

5. A ventilator comprising a pipe, an element disposed above and laterally from said pipe, said element having tapered channels on its exterior, tubular passages coacting with said channels for deflecting the air currents in substantially vertical paths, and a cap within the element and spaced therefrom for protecting the pipe and providing an outlet therebetween.

6. A ventilator comprising a pipe, an element disposed above and laterally from said pipe, said element having curved tapered channels on its exterior, tubular passages coacting with said channels for deflecting the air currents in substantially vertical paths, and a cap within the element and spaced therefrom for protecting the pipe and providing an outlet therebetween.

7. A ventilator comprising a pipe, an element disposed above and laterally from said pipe, said element having oppositely tapered channels on its exterior, tubular passages coacting with said channels for deflecting the air currents in substantially vertical paths, and a cap within the element and spaced therefrom for protecting the pipe and providing an outlet therebetween.

8. A ventilator comprising a pipe, an element disposed above and laterally from said pipe, said element having oppositely curved tapered channels on its exterior, tubular passages coacting with said channels for deflecting the air currents in substantially vertical paths, and a cap within the element and spaced therefrom for protecting the pipe and providing an outlet therebetween.

In testimony, that I claim the foregoing as my invention, I have signed my name this 17th day of April, 1925.

ARTHUR MILLER.
